UNITED STATES PATENT OFFICE.

JOHN M. FENNERTY, OF WASHINGTON, DISTRICT OF COLUMBIA.

RAILWAY-CHAIR.

SPECIFICATION forming part of Letters Patent No. 335,067, dated January 26, 1886.

Application filed June 29, 1885. Serial No. 170,140. (No model.)

To all whom it may concern:

Be it known that I, JOHN M. FENNERTY, a citizen of the United States of America, residing at Washington, in the District of Columbia, have invented certain new and useful Improvements in Railway-Chairs, of which the following is a specification, reference being had therein to the accompanying drawings.

My invention is an improved rail-chair, and embraces the following novel features: A metallic bolster-block having a socket-groove one side and the bottom of which conform, respectively, to the transverse section of the web and lower side flanges of the rail, said web side being counterbraced on the outside by arching buttress-like supports which rise vertically from the surface of said blocks, of which they are a solid portion; also, a sliding wedge-plate having an upper and lower longitudinal flange on its front side, between the inclined ledges of which an open slot-space is thus made which conforms fittingly to the flanged edge of said socket-groove of the chair-block; and, finally, pivoted to one end of the base of said block is a vertically-moved latching-catch, which rests its loose end perpendicularly against the front of said wedge-plate, between a projecting knob upon its surface and a contiguous end of its said upper overlapping and oversliding flange, all of which and their purposes are hereinafter more fully described, and illustrated by the accompanying drawings, in which like letters designate identical parts of said invention in the different figures, respectively.

Figure 1 is an end view of said chair, showing the rail-flange-inclosing socket-groove, the side of one of the said buttress-braces, the flange edge of said socket-groove directly underneath the over and under sliding ledge-flanges of said wedge-plate and the said pivotal latching-catch. Fig. 2 is an elevation of the front side of said bolster-block and the said sliding wedge-plate directly above. Fig. 3 is an elevation of the obverse side of said chair-block, showing said buttress-braces supporting the outer side of the rail-web plate; and Fig. 4 is a perspective view of said invention, showing the relative positions of its parts with an enlocked railway-track rail.

The letter A represents the said bolster-block, forming the rail-inclosing and joint-

supporting chair. It is made all in one piece, with the longitudinal socket-groove b cut entirely through its whole length, as shown, so as to conform to the transverse shape of the inclosed and jointing rails and allow their abutting ends to be easily slipped in and out, for adjustment or repair of the track, without any binding or clamping of their webs or flanges. The web-supporting side of said groove is counterbraced against any spreading pressure upon the rails by the vertically-arching and laterally-supporting buttress-braces c, which rise from the concave surface of the chair-block, of which they are one piece, 60 perpendicularly against the outside of said rail-web support, as shown. The lateral edges of the base of said block are beveled outward, in order to form a dovetailed joint within the conformably jointing and leveling slot cut into 65 the top of the track-tie, as shown; and said base is further secured from any longitudinal slipping within said jointing-slot by rail-spikes driven or by bolts screwed through said base into the tie-block beneath. In order to firmly secure and hold said abutting rail-joints in proper vertical position and prevent the jar of passing trains from disturbing the fixedness of the said inclosing chair-blocks after one of said bolsters has been fastened, as aforesaid, into 70 its bearing tie or block, and after said rail-joint has been adjusted by slipping the opposite ends of the two abutting rails longitudinally into said socket-groove until said ends nearly meet, the said wedge-plate D is provided, which consists of a sliding plate of suitable size and material, and has formed on its front side and projecting at an inclination therefrom the counter-pair of longitudinal flanges e and f, which are sufficiently separated by an intervening grooved space to conform to the longitudinal flange-edge of said socket-groove b, as shown, and thereby allow said conformedly-shelving flanges e and f to respectively slide under and over the correspondingly-shelving edge of said socket-groove until the farther or entering end of said overlapping flange is stopped against the check-spur s, intentionally projecting therefrom from the grooved flange beneath, and the near ends of both lapping flanges are brought flush with the near end of the chair-block. Mean-

while, in order to jam said smoothly-laid and 5 rectangularly-shaped sliding plate tightly against the continuously-jointed webs of the inclosed track-rail and between their bearing and lower flanges, the roof of said upper shelving-flange, *f*, is made slightly thicker on its near or following end, thereby wedging the same between the rail-flanges with the thrust of said sliding plate. This sliding plate, with its 10 shelving and wedging flanges, makes a counter-bracing support, with the opposite web-supporting side of said chair-groove, to the inclosed track-rails against any lateral movement whatever, while said counter-supporting 15 chair does not prevent any necessary vertical motions of the rails from passing trains or the longitudinal expansion or contraction of the same from atmospheric changes. In order to give additional security to the steadfastness of 20 said rail-joint-supporting elements of said chair-block and prevent any possible slipping of said wedge-plate from its proper position in connection with said rails and bolster, the latching-catch *g* is furnished, which consists 25 of a suitably sized and shaped pivotal plate or bar secured to the wedge-plate-entering end of the basal part of said chair-block by a check-screw turning in a curved slot cut through said pivotal plate, as shown, thereby to make 30 the locking adjustment of its loose end perpendicularly against the front of said wedge-

plate, while conforming to the slightly-varying thickness or present expansion of the rail-webs. Thus said rail-chair, by means of its elemental parts, hereinbefore described, becomes 35 a very simple, effective, easily and quickly adjusted, and steadfast support to the abutting joints of track-rails, without the necessity of any aid from fish-plates, bored rail-webs, screw-bolts, nut-locks, or any other of the continually-loosening and deteriorating contrivances now used in the thereby expensive construction and repair of railway-tracks, especially in the present expedited travel of railway-trains. Therefore--

40 What I claim as new, and desire to secure by Letters Patent, is—

The railway-chair composed of the two conforming parts herein described, the bolster-block having the socket-groove, buttress-braces, and slotted latching-catch, and the 45 sliding wedge-plate having the shelving-flanges, all made to adjustably co-operate with the abutting and jointing ends of railway-track rails, substantially as and for the purposes herein specified.

In testimony whereof I affix my signature in presence of two witnesses.

JOHN M. FENNERTY.
